DESIGN FOR A SLICING MACHINE OR THE
LIKE

Thormod Jensen, Laurelton, Long Island, N. Y.,
and Herbert Rosengren, Woodcliff Lake, N. J.,
assignors to American Machine & Foundry
Company, a corporation of New Jersey

Original application May 6, 1938, Serial No.
D-77,042. Divided and this application Sep-
tember 12, 1939, Serial No. 87,158

Term of patent 14 years

To all whom it may concern:

Be it known that we, Thormod Jensen, a citizen of the United States of America residing at Laurelton, in the county of Queens and State of New York, and Herbert Rosengren, a citizen of the United States of America residing at Woodcliff Lake, in the county of Bergen and State of New Jersey, have invented a new, original, and ornamental Design for a Slicing Machine or the like, of which the following is a specification, reference being had to the accompanying drawings, forming part thereof. This application has been divided from our co-pending application Serial Number D-77,042, filed May 6, 1938.

The drawings show in:

Fig. 1 a front perspective view of a slicing machine or the like, illustrating our new design;

Fig. 2 a similar view taken from the other side of the same;

Fig. 3 a view thereof in end perspective, looking toward the left-hand end of Fig. 1; and

Fig. 4 a similar view thereof, looking toward the left-hand end of Fig. 2.

We claim:

The ornamental design for a slicing machine or the like, substantially as shown and described.

THORMOD JENSEN.
HERBERT ROSENGREN,
